UNITED STATES PATENT OFFICE.

MAXIMILIAN CHARLES SCHWEINERT, OF WEST HOBOKEN, NEW JERSEY, AND HENRY P. KRAFT, OF NEW YORK, N. Y., ASSIGNEES, BY MESNE ASSIGNMENTS, TO A. SCHRADER'S SON, INCORPORATED, OF NEW YORK, N. Y., A CORPORATION OF NEW YORK.

WATER-BOTTLE STOPPER.

1,076,162.

Specification of Letters Patent.

Patented Oct. 21, 1913.

Application filed February 28, 1906. Serial No. 302,889.

To all whom it may concern:

Be it known that we, MAXIMILIAN CHARLES SCHWEINERT, residing in West Hoboken, in the county of Hudson and State of New Jersey, and HENRY P. KRAFT, residing in the borough of Brooklyn, county of Kings, city and State of New York, citizens of the United States, have invented certain new and useful Improvements in Water-Bottle Stoppers, of which the following is a specification.

This invention relates to water bottle stoppers or similar devices, and aims to provide certain improvements therein.

Our invention is especially applicable to that type of stopper in which the valve seat is formed at the lower end of the socket member, the latter being extended upwardly a considerable distance above the point of its connection with the neck of the bottle, and being provided with suitable ports for the entrance and discharge of water. In this construction of stopper the part which constitutes the stopper proper need not be removed from the socket when the bottle is to be filled or emptied, it being only necessary to screw it upwardly until it passes the ports of the socket member.

Notwithstanding the fact that it is not necessary to remove the stopper from its socket, this is often accidentally done in the operation of filling or emptying, with the result that the stopper frequently becomes lost or misplaced.

Our invention aims to provide a construction in which such accidental separation is impossible, and in which there is no liability of loss of any of the parts.

Our invention also includes certain other features of improvement which will be hereinafter specified.

In the drawings which illustrate certain embodiments of our invention, Figure 1 is a vertical section of the neck and funnel of a hot water bag showing our improved construction of stopper applied thereto; Fig. 2 is a view of the stopper and retaining cap detached, the stopper being shown in elevation and the cap in vertical section; Fig. 3 is a view showing the method of uniting the cap and stopper. Figs. 4 and 5 are detail views illustrating the locking means for the cap, Fig. 4 being in section and Fig. 5 in elevation. Fig. 6 is a sectional view of a modification.

In the drawings let A designate a hot water bag of any suitable construction having a neck *a* and a flaring mouth or funnel *b*. The socket member B of the stopper is shown as formed of a sheet metal tube having at its lower end an inturned flange *c* adapted to form a valve seat, and having its wall screw-threaded throughout its length to receive the stopper proper C. The socket member B is vulcanized or otherwise connected to the neck *a* of the bottle at its lower end, and is extended upwardly therefrom a sufficient distance to permit the stopper C to move past the radial ports *d* so that water may be admitted or discharged through such openings without removing the stopper from such member. The stopper C may be of any desired construction, that shown consisting of two sections *e*, *f*, of sheet metal, the lower section *f* being formed with screw threads 75 to engage those of the socket member B. The section *f* carries on its lower face a disk *g* of packing material designed to close the opening in the seat *c* when the stopper is in its lower position.

To prevent the withdrawal of the stopper from the socket we provide a retaining device which is preferably adapted to be connected to the upper end of the socket member and to engage a suitable shoulder or projection upon the stopper. Such retaining device may be constructed in various ways, but in the drawing we have shown the form we prefer to employ which comprises a cap D having a vertical flange *h* which is screw-threaded to engage the upper end of the socket member, and a horizontal flange *i* which is adapted to engage a shoulder *j* formed at the upper end of the screw-threaded section *f* of the stopper. The flange *i* extends inwardly a sufficient distance to render it impossible to remove the stopper by working the screw-threaded portion thereof through the opening in the flange.

According to our invention we form the cap D (or other similar device) as an inseparable part of the stopper C, so that the cap cannot be lost or mislaid. In the construction shown the stopper is provided with a handle E which is preferably of greater width than the diameter of the opening in the cap D, so that while the cap may freely move along the section *e* of the stopper it is prevented from slipping off the outer end thereof by the handle E.

The cap D may be applied to the stopper in various ways, as for instance, by forming it in its completed shape as shown in Fig. 1 and slipping it over the section e either before the handle is connected therewith, or after the handle is applied and before the section e is united to the section f. Preferably, however, we adopt the method illustrated in Figs. 2 and 3, wherein the parts are shown before and just after the application of the cap to the stopper. According to this method we initially construct the cap D in the form of a screw-threaded tubular section, and preferably give the upper part of the cap D which afterward forms the flange i a preliminary bending such as shown in Fig. 2. This bending operation restricts the effective opening through the cap so that the latter will just pass through the screw-threaded portion of the stopper. When the cap has been placed in position on the stopper, the flange i is then bent inwardly by a suitable tool to such extent that its opening is so restricted as to render separation impossible. This operation is indicated in Fig. 3, the original position of the flange being shown in dotted lines. By this method the stopper may be completely formed with its handle riveted to its body, and the whole given the usual coating of nickel plate, before the application of the cap D. The latter also may be plated in the form shown in Fig. 2, and in this condition applied to the stopper and its flange i afterward bent to proper position without perceptibly marring the finish of the cap. This mode of application hence has a considerable advantage in practice over those hereinabove referred to.

Our invention also provides an important feature of improvement in connection with the mode of connection of the cap to the socket member. Ordinarily a plain screw-threaded connection is sufficient to securely hold the cap in place on the socket member. It is possible if the cap is carelessly applied by the user, that it may not be screwed firmly enough in place to resist the unscrewing action which the stopper exerts upon it after the stopper contacts with the cap. To obviate the possibility of such accidental unscrewing, we provide a lock for the cap which, while it prevents any unintentional dislodgement of the cap, still permits its intentional separation from the socket member by hand when necessary or desirable, as for instance, for inspecting or replacing the disk g. The construction which we prefer to provide for this purpose is illustrated in detail in Figs. 4 and 6. As shown, the upper wall of the socket member is cut to form a spring tongue m, the outer end of which is bent outwardly so that it projects slightly beyond the wall of such member as

indicated at n. The cap D is provided with a recess or hole o, which when the cap is screwed home engages the projection n, the tongue m springing inwardly a sufficient extent to permit such engagement. When the stopper is in its upper position, however, as illustrated in Fig. 1, it prevents the inward movement of the tongue m and hence prevents disengagement of the recess o from the projection n. As it is only when the stopper is in the position of Fig. 1 that there is any tendency to unscrew the cap it will be observed that the latter is firmly held in position against accidental displacement. If it is desired to remove the stopper, the latter is screwed downwardly until its screw-threaded portion passes from behind the tongue m so that the latter is free to spring inwardly, at which time the application of sufficient force to the cap will cause the recess to become disengaged from the projection. The latter is preferably formed with inclined surfaces to facilitate such disengagement.

Our invention also provides certain improvements in the construction of the stopper proper. In stoppers of the general construction illustrated in Fig. 1 the stopper proper must be elongated to a considerably greater extent than that ordinarily necessary in order to provide for the greater degree of movement which is required. In the particular construction shown in Fig. 1 the sections e and f are separately formed and united to each other by soldering. This method of connection is comparatively costly and results in a less secure union than is sometimes desirable. By our present invention we obviate this difficulty and produce an extremely strong construction of stopper which may be very cheaply manufactured. As shown in Fig. 6 we form one of the parts as e with an outwardly extending flange p, and the other of the parts as f with an outwardly and upwardly extending flange q the parts being united in this condition and the upper part of the flange q (shown in dotted lines) being subsequently bent over upon the flange p by a suitable tool. This connection affords an extremely strong and rigid union between the parts. While we may so form the flanges p and q that they do not extend beyond the section f in the finished stopper, we prefer to form them in the manner shown so that the stopper when completed is provided with an annular flange such as illustrated. This flange forms an efficient shoulder or projection for engagement with the cap D. When this construction is adopted the socket member B' is provided with an enlarged portion s which is designed to receive the flange thus formed. In this construction the mode of applica-

tion of the cap to the stopper may be that before described, a sufficiently large opening being left in the cap in this instance to pass over the flange of the stopper.

5 It will be observed that by our invention we provide a stopper having a retaining cap inseparably connected thereto under all conditions of use, so that it is impossible for the cap to become lost or misplaced apart from 10 the stopper. It will also be observed that the stopper is firmly held within its socket so that it cannot be worked out of the cap either accidentally or intentionally and that the cap is securely locked on the socket member 15 so that it cannot be separated therefrom unless it is the intention to do so, and then only by a special mode of manipulation. It will also be observed that our invention provides an extremely strong and cheap form of 20 stopper, and a novel form of socket member which is especially adapted for use in connection therewith.

Although we have described in detail certain embodiments of our invention, we do 25 not wish to be limited thereto, as various modifications may be made therein without departing from our invention.

What we claim is:—

1. In a water bottle stopper, a socket member, a stopper movable therein, a device engaging said socket member and adapted to retain said stopper therein and means for preventing the removal of said device when the stopper is in contact therewith, and for 35 permitting the intentional removal thereof when the stopper is free therefrom.

2. In a water bottle stopper, a socket member, a stopper movable therein, a screw-threaded retaining member engaging said 40 socket member and having a recess formed therein, and a lock for said retaining member acting to hold it in position on said socket member said lock comprising a spring tongue formed on said socket member and 45 adapted to engage a recess in said retaining member.

3. In a water bottle stopper, a socket member, a stopper screwing therein, a screw-threaded retaining cap for said stopper 50 adapted to engage said socket member, said socket member being formed at its upper end with a spring tongue, and said cap being formed with a recess adapted to receive the end of said tongue, said parts being formed 55 to prevent the disengagement of said tongue and recess when said stopper is in its uppermost position.

4. A water-bottle closure, comprising a socket having a screw-threaded tubular lower 60 portion and a tubular upper portion of larger diameter than said lower portion, a stopper having a screw-threaded lower por-

tion adapted to engage the screw-threaded portion of said socket, an upper portion of less diameter than said screw-threaded portion, and a shoulder between said upper and lower portions of the stopper, said socket having means thereon for engaging said shoulder to prevent detachment of said stopper from said socket. 70

5. A water-bottle closure, comprising a socket having a screw-threaded tubular lower portion and a tubular upper portion of larger diameter than said lower portion, a stopper having a screw-threaded sheet-metal 75 lower portion adapted to engage the screw-threaded portion of said socket, an upper sheet-metal portion of less diameter than said screw-threaded portion, and a joint upon the outside of said portions uniting 80 said portions, said joint constituting a shoulder between said upper and lower portions of the stopper, said socket having means thereon for engaging said shoulder to prevent detachment of said stopper from said 85 socket.

6. A water-bottle closure, comprising a socket having a screw-threaded tubular lower portion and a screw-threaded tubular upper portion of larger diameter than said lower 90 portion, a stopper having a screw-threaded lower portion adapted to engage the screw-threaded portion of said socket, an upper portion of less diameter than said screw-threaded portion, a shoulder between said 95 upper and lower portions of the stopper, and a screw-threaded cap engaging the screw-threads of the upper portion of said socket for engaging said shoulder to prevent detachment of said stopper from said socket. 100

7. A water-bottle closure, comprising a socket having a screw-threaded tubular lower portion and a screw-threaded tubular upper portion of larger diameter than said lower portion, a stopper having a screw-threaded 105 lower portion adapted to engage the screw-threaded portion of said socket, an upper portion of less diameter than said screw-threaded portion, a shoulder between said upper and lower portions of the stopper, and a screw-threaded cap engaging the screw-threads of the upper portion of said socket for engaging said shoulder to prevent detachment of said stopper from said socket, said cap having means thereon for preventing unscrewing thereof. 110

In witness whereof, we have hereunto signed our names in the presence of two subscribing witnesses.
